UNITED STATES PATENT OFFICE.

WILLIAM P. SWEENEY, OF MINNEAPOLIS, MINNESOTA.

UNION GARMENT.

Application filed July 9, 1927. Serial No. 204,550.

This invention relates to garments and particularly to union garments in the nature of overalls.

It is the main object of this invention to provide a garment having a quickly and readily securable flap adjacent the waist portion thereof which flap is capable of considerable expansion transversely of the waist portion of the garment.

It is the further object of this invention to provide certain novel improvements on my "union suit" patented by me on November 14, 1922, Patent No. 1,435,736. The purpose of said patent was to provide a one piece garment having an opening flap forming a drop seat adjacent the waist portion of the garment, which flap could be quickly and easily opened and closed by a special form of fastening device. The more specific object of this invention is to provide in such a garment means for permitting the said flap to be considerably expanded to conveniently permit the same to be widely opened.

These and other objects and advantages of the present invention will more fully appear from the following description made in connection with the accompanying drawings, wherein like reference characters refer to the same or similar parts throughout the various views and, in which,

Fig. 1 is a rear view of the waist portion of a garment embodying the present invention and showing the drop seat of the garment closed as in normal wearing position;

Fig. 2 is a horizontal section taken on the line 2—2 of Fig. 1, as indicated by the arrow;

Fig. 3 is a horizontal section taken on the line 3—3 of Fig. 1, as indicated by the arrow;

Fig. 4 is a rear view similar to Fig. 1, but showing the drop seat of the garment in opened up position;

Fig. 5 is a detailed view illustrating a type of fastening means that may be used for closing one of the openings in the garment, and

Fig. 6 is a vertical section taken on the line 6—6 of Fig. 1, as indicated by the arrow.

Referring to the drawings, a portion of a one piece union garment in the nature of overalls is shown comprising the portion 7 above the waist and the portion 8 below the waist. The portions 7 and 8 are sewed or otherwise secured together at the waist sec-

tion of the garment at preferably the front side thereof and are unsecured at preferably the rear side thereof. Accordingly, the garment can be considered as having a transverse opening extending approximately half-way around the waist section of the garment at the rear thereof. The front and rear portions of the garment are divided along one side adjacent the waist section to form a substantially longitudinal opening at one side of the garment, the right side as viewed in Figs. 1 and 4 of the drawings. The said transverse and longitudinal openings connect with one another to form a triangular flap 9 in the portion 8. As the longitudinal opening at the right side of the garment extends upwardly some little distance from the waist line into the portion 7 of the garment, a small flap 10 is formed on the upper portion 7 of the garment. Co-operating fastening means are provided on the flaps 9 and 10 for securing the same together and to the front of the portion 8 of the garment. In the embodiment shown, the side fastening means comprise a button 11 secured to the inner side of the flap 10, a buttonhole 12 formed on a projecting tab on the flap 9 and a buttonhole 13 formed at the front right top corner of the portion 8. When it is desired to close the longitudinal opening at the right side of the garment, the button 11 may be engaged in the buttonhole 13, whereupon flap 9 may be drawn upwardly from the position illustrated in Fig. 5 to the position illustrated in Fig. 1 and the button 11 engaged with the buttonhole 12.

The front and rear portions of the garment are divided at the other side thereof adjacent the waist line, the left side as viewed in Figs. 1 and 4, to form a second longitudinal opening which extends both upwardly into the portion 7 of the garment and downwardly into the portion 8 of the garment. A tape 14 of comparatively short length is sewed or otherwise secured to the inner side of the lower edge of the left hand corner of the rear section of portion 7 and the said tape is folded against itself and is secured as best illustrated in Fig. 4 to the upper rear left hand corner of the portion 8. A small triangular flap 15 will thereto be formed at the lower rear left hand corner of the portion 7, while a small triangular flap 16 will be formed at the upper rear left hand corner of the portion 8. Co-operating fastening means are

provided for securing the flaps 15 and 16 together and to the front sides of portions 7 and 8 to close the left side opening in the garment. In the embodiment shown, two 5 buttons 17 and 18 are secured to the upper corner of flap 16, co-operating button holes 19 and 20 are provided in the front lower left hand corner of portion 7, and a button hole 25 is provided at the corner of flap 15. 10 To close the left side opening, the button 17 will be engaged in the button hole 25, whereupon the two buttons 17 and 18 will be engaged in the respective buttonholes 19 and 20. If desired, a button and buttonhole may 15 be provided in the front and rear sections of portion 8 below the waist line at the left hand side of the garment for further closing the longitudinal opening at the left side of the garment. For the purpose of description, the opening between the upper section 20 and the lower section of tape 14 may be considered as a secondary transverse opening in the garment spaced a short distance above the above described main transverse opening. 25

The lower edge of portion 7 at the rear side is provided with a strip 21 which extends substantially across the rear side of the garment at the waist line and is secured 30 to the portion 7 from the corner of flap 10 to the right corner of tape 14 and to the lower section of tape 14. A similar strip 22 is secured to the upper edge of the rear section of portion 8 adjacent the waist line 35 of the garment to oppose the strip 21. Co-operating fastening devices 23 are secured to the free edges of both the strips 21 and 22. Each of the fastening devices 23 comprises 40 a series of closely arranged locking members which when brought together by means of a locker member 24 fitting over fastening devices 23-28, as illustrated in Fig. 5, interengage with each other and become locked so that the same cannot be separated by 45 stress exerted in a line normal to their length. The various members of the fastening devices 23 can be readily separated, however, by a spreading stress applied thereto by either pulling the right hand 50 flaps 9 and 10 away from each other or by moving the locking member 24 to the left as viewed in Figs. 1, 4 and 5 of the drawings. The tapes 21 and 22, fastening devices 23 and the locking member 24 may be called a 55 hookless fastener, and the same is a development of the W. L. Judson "clasp locker for shoes," patented March 31, 1896, Patent No. 557,208. It is sufficient for the present invention to know as above stated, that the 60 hookless fastener can be readily separated by a spreading stress applied to the strips 2, at the right of locking member 24 or by moving locking member 24 to the left and that the main transverse opening at the rear 65 of the garment will be quickly and readily

closed by the fastening members 23 when the locking member 24 is moved to the right. It will be seen by use of the hookless fastener structure that the flaps 9 and 10 can be almost instantly opened and just as easily and quickly closed. It will also be observed 70 that the flaps 15 and 16 may be readily and quickly opened and closed by disengagement or engagement of the various buttons 17 and 18 with the various buttonholes. 75

It will be understood, of course, that instead of providing the above described structure at the rear of the garment, the same may be provided at the front or at other points on the garment and that the parts at 80 the right side of the garment may be provided at the left side of the garment and vice versa. It will also be understood that various types of fastening means may be substituted for the buttons and buttonholes 85 specified and that the hookless fastener above described is capable of considerable modification. 90

A garment is provided which has formed 95 therein a drop seat which can be easily and readily opened or closed and when opened will be capable of considerable expansion transversely of the waist of the wearer. Although the embodiment of the invention illustrated has been worked out particularly 100 for use on overall garments, the invention is capable of being applied to many uses. The inventor particularly contemplates use of the invention in connection with sailors' trousers such as are now commonly used in the 105 United States Navy, for quickly and readily closing the forward opening therein. 110

It will, of course, be understood that various changes may be made in the form, details, arrangement and proportions of the 105 various parts without departing from the scope of the present invention, which, generally stated, consists in the matter shown and described and set forth in the appended claims. 110

What is claimed is:

1. A union garment having a substantially transverse opening therein extending partly around the waist portion thereof, a substantially longitudinal opening at the waist portion spaced slightly from one end of said transverse opening, and a substantially longitudinal opening at the waist portion joining the other end of said transverse opening to form a main flap, strips secured to both edges of said garment adjacent said transverse opening, each of said strips carrying at its free edge a series of interengaging fastener members, said members being so constructed and arranged that when closed they are locked against separation by a stress normal to the length of said strips but separable by a spreading movement applied to the ends of said strips adjacent said last mentioned longitudinal opening to open said main flap, 120 125 130

said strips having co-operating interengaging fastening means on the portions thereof adjacent said first mentioned longitudinal opening, whereby when said fastening means are disengaged and said strips have been separated the main flap of said garment can be considerably expanded.

2. A union garment having a substantially transverse opening therein extending part-way around the waist portion thereof, a substantially longitudinal opening at the waist portion spaced slightly from one end of said transverse opening and extending upwardly and downwardly therefrom, a short transverse opening a short distance above said first mentioned transverse opening and connecting with the central portion of said longitudinal opening to form small flaps at one side of the garment, co-operating interengaging fastening means on said garment for releasably closing said longitudinal opening and said last mentioned transverse opening, strips secured to both edges of said garment adjacent said first mentioned transverse opening, said strips carrying at their free

edges a series of interengaging fastener members, said members being so constructed and arranged that when closed they are locked against separation by a stress normal to the length of said strips but separable 30 by a spreading movement applied to the ends of said strips opposite said longitudinal opening, whereby when said first mentioned fastening means are released from each other and said last mentioned fastener members 35 are separated from each other, the waist portion of said garment may be considerably expanded.

3. The structure defined in claim 2, said garment having a longitudinal opening at 40 the opposite side thereof from said first mentioned longitudinal opening and connecting with said first mentioned transverse opening to form a flap and co-operating interengaging fastening means for releasably 45 closing said last mentioned longitudinal opening.

In testimony whereof I affix my signature.

WILLIAM P. SWEENEY.
